SECONDARY BATTERY

Horace De Martis and Sydney James Clark, New Malden, England, assignors to The Young Accumulator Company (1929) Limited, New Malden, England, a British company

Application December 4, 1935, Serial No. 52,900
In Great Britain December 12, 1934

6 Claims. (Cl. 136—147)

This invention relates to improvements in and pertaining to secondary batteries and refers, more particularly, to an improved envelope for the electrodes or plates thereof and to a method of manufacturing the said envelopes.

An envelope according to the present invention consists of two spaced sheets of perforated material which are united to each other along marginal portions by means of soft rubber which 10 keys in the perforations in the margins and provides a resilient surround for the assembly comprised by the envelope and plate.

In the preferred form of the invention the perforated sheets are made of ebonite. Each 15 sheet in its fully or partly vulcanized state is conjoined by vulcanization to a sheet of porous ebonite. The porous ebonite has the effect of preventing the passage of material that disintegrates from the electrode whilst freely permitting of the flow of electrolyte; and the perforated ebonite, apart from its function of providing a key for the sealing medium, gives 20 strength and flexibility to the porous ebonite.

The size of the porous ebonite is preferably 25 smaller than that of the perforated ebonite to expose marginal portions of perforated ebonite. In this arrangement the sealing medium becomes locked to the said margins in that it is able to flow round both faces thereof and flow into 30 and unite in the perforations or slots.

The arrangement and sealing of the sheets according to the invention adds to the mechanical 35 strength of the whole envelope or separator and enables to be made a satisfactory sealing which does not protrude beyond the total thickness of the envelope.

The soft rubber consists of any suitable mixture, for example, a rubber-sulphur mixture having a total sulphur content of approximately 40 2 to 3%. This mixture provides a cushion having the required degree of resiliency to minimize mechanical shocks and effectively unites the sheets comprising the envelope.

The envelopes may be separated in the battery 45 container in any suitable manner. For example, the container may be grooved and the envelopes fitted into the grooves, or the outer faces of the envelopes may be ribbed and the ribs of adjacent 50 envelopes made to contact with each other. In any case the arrangement is such that the outer side faces of the cushions are flush with the outer side faces of their envelopes so that the necessary flow of the electrolyte from bottom to top of 55 the battery is not prevented nor hindered.

The invention will now be described with reference to the accompanying drawing wherein:

Fig. 1a shows an end elevation and a Fig. 1b shows a front view of a sheet 1 of perforated ebonite joined by vulcanizing to a sheet 2 of porous ebonite, part of the perforated ebonite being broken away in the front elevation in order to expose the porous sheet;

Fig. 2 is a perspective view of an envelope constructed according to the present invention from composite sheets as that illustrated in Fig. 1, the envelope containing a battery electrode 3;

Fig. 3 is a sectional elevation, on an enlarged scale, of a part of the assembly illustrated in Fig. 2, this elevation showing the relative positions of the sheets 1 and 2 with respect to the electrode 3 and the manner in which the composite sheets are sealed together and the whole is cushioned;

Fig. 4 is a side elevation of a composite sheet modified with respect to Fig. 1 in that the porous sheet 2 is smaller than the perforated sheet 1 in order to provide a perforated margin 4 along the vertical sides and the bottom of the composite sheet;

Fig. 5 is a sectional elevation on a larger scale of part of an envelope constructed from sheets as that illustrated in Fig. 4, said envelope containing an electrode 3;

Fig. 6 illustrates a piece of rubber strip used for uniting or sealing the composite sheets and for forming the cushion;

Fig. 7 is a plan view of the lower part of a mould for forming the said envelope; and

Fig. 8 is a sectional elevation of the said mould and its top plate in readiness for moulding an envelope according to the present invention containing the electrode 3.

The sheets 1 in their fully or partly vulcanized state are conjoined by vulcanization to the sheets 2 of porous ebonite.

To make one form of envelope according to the invention a composite sheet (Fig. 1) slightly smaller than the recess 5 in the lower part 6 of the mould is laid, porous side downwards, in the said recess so that a margin 7 is provided around two sides and an end of the sheet. The plate 3 is then placed on the perforated sheet in the mould. The face of this plate is smaller than the composite sheet so that the perforated sheet is left with margins 8 exposed within the margins 7, the connecting tongue of the said plate being received in a recess 9 in the mould part 6. A second composite sheet similar to the first is then laid perforated side downwards on the plate 3. 55

In this manner marginal portions 8' corresponding to the margins 8 are provided on the perforated underface of the second composite sheet.

At suitable stages during the procedure above 5 set forth, or at the end of this procedure, soft rubber strip 10 is forced with the aid of a suitable bladed tool into the U-shaped space comprising the margins 7.

The top plate 11 of the mould, which plate is 10 hinged to the part 6 at 12, is then lowered onto the said part 6 and the closed mould subjected to heat and pressure.

The plate 11 has a false plate or block 13 on the underside of which is a U-shaped flange 14 slidably fitting into a groove 15 of similar shape in the plate 11. The groove 15 and the flange 14 are 15 so located that they coincide exactly with the margins 7.

The heat has the effect of softening and vulcanizing the strip 10; and the pressure that of 20 forcing the flange 14 to squeeze the soft rubber into the space between the margins 8 and 8' and into such perforations as lie within the margins. In this manner each composite sheet is sealed 25 or united to the other along three of its edges. The rubber finds a key in the perforations in the margins 8 and 8', whilst the rubber which remains in the space formed by the margins 7 provides a surround 10' around three sides of the envelope.

30 After the heat and pressure have been applied the mould is removed from the press and opened to permit of the removal of the envelope and plate 3, the false plate 13 being returned to its original position by means of compression springs 16 the 35 action of which is limited by stop studs 17.

The strip 10 is composed of soft rubber of any 40 suitable mixture, for example, a rubber having a total sulphur content of approximately 2 to 3% so as to remain resilient after vulcanization. In this manner the surround 10' provides a cushion 45 for the whole assembly and the soft rubber in the space between the margins 8, 8' a cushion for the electrode besides uniting the two composite sheets.

45 Composite sheets such as that illustrated in Fig. 4 are made into envelopes in substantially the same manner as already described with reference to Figs. 1 to 3 and 6 to 8. In the case of Fig. 4, however, the soft rubber also spews around the 50 margins 7 of the composite sheets and passes into the perforations in the margin where it units with rubber spewing into the space between the margins 8, 8' (Fig. 5). In this manner the rubber is 55 locked to the composite sheets and the whole assembly and the electrode are cushioned in the manner already described.

The sheet 2 illustrated in Fig. 4 is ribbed as 60 shown at 18. The sheets 2 illustrated in Figs. 1, 2 and 3 are preferably ribbed in like manner and the moulds correspondingly shaped. The ribs provide spacers between adjacent envelopes arranged in a battery container. The sides of the 65 soft rubber are, however, flush with the outer faces of the perforated sheets so as not to seal or obstruct the bottoms of the spaces formed between the envelopes by the said ribs 18.

If desired a plane upper plate may replace the plate 11 and the block 13.

70 The drawing shows perforations consisting of circular holes: the perforation may be of any suitable shape e. g., elongated (or slotted) openings or square holes.

What we claim is:—

75 1. An envelope for an electrode of a secondary

battery, comprising two spaced sheets of perforated ebonite, a sheet of porous ebonite conjoined by vulcanization to the outer face of one of said perforated sheets and a second sheet of porous ebonite similarly conjoined to the outer face of the 5 other perforated sheet, and a soft rubber surround, said surround keying in the perforations in the marginal portions of said perforated ebonite sheets to seal the sheets together and extending beyond the edges thereof to provide a cushioning means around the envelope.

2. An envelope for an electrode of a secondary battery, comprising two spaced sheets of perforated ebonite, a sheet of porous ebonite conjoined by vulcanization to the outer face of one of said 15 perforated sheets and a second sheet of porous ebonite similarly conjoined to the outer face of the other perforated sheet, said porous ebonite sheets being smaller than said perforated sheets and located thereon to expose perforated 20 marginal portions of said perforated sheets, and a soft rubber surround, said surround keying in the perforations in the marginal portions of the outer and inner faces of said perforated sheets.

3. An envelope for an electrode of a secondary 25 battery, comprising two spaced sheets of perforated ebonite, a sheet of porous ebonite conjoined by vulcanization to the outer face of one of said 30 perforated sheets and a second sheet of porous ebonite similarly conjoined to the outer face of the other perforated sheet, said porous ebonite sheets being smaller than said perforated sheets and located thereon to expose perforated 35 marginal portions of said perforated sheets, and a soft rubber surround, said surround keying in the 40 perforations in the marginal portions of the outer and inner faces of said perforated sheets to seal said sheets together and extending beyond the edges thereof to provide a cushioning means.

4. An envelope for an electrode of a secondary 45 battery, comprising two spaced sheets of perforated ebonite, a sheet of porous ebonite conjoined by vulcanization to the outer face of one of said 50 perforated sheets and a second sheet of porous ebonite similarly conjoined to the outer face of the other perforated sheet, said porous ebonite sheets being smaller than said perforated sheets and located thereon to expose perforated 55 marginal portions of said perforated sheets, and a soft rubber surround, said surround keying in the 60 perforations in the marginal portions of the outer and inner faces of said perforated sheets to seal said sheets together, extending beyond the edges thereof to provide a cushioning means, and having a thickness such that its side faces do not 65 extend beyond the outer faces of the envelope.

5. A unit for use in a secondary battery comprising a plate electrode in an envelope according to claim 2, said surround providing a cushion 70 around said electrode as well as around said envelope.

6. An envelope for an electrode of a secondary 75 battery, comprising two spaced sheets of perforated material, a sheet of porous material indi- 80 visibly united to the outer face of one of said perforated sheets, a second sheet of porous material indivisibly united to the outer face of the other of said perforated sheets, and a soft rubber 85 surround keying the perforations in the marginal portions of said perforated sheets to seal the sheets together.
